INVENTOR

PETER A. POPPE

Spear, Middleton, Donaldson, Hall ATTORNEY

UNITED STATES PATENT OFFICE.

PETER AUGUST POPPE, OF COVENTRY, ENGLAND.

VALVE MECHANISM FOR INTERNAL-COMBUSTION ENGINES.

Application filed March 29, 1923. Serial No. 628,589.

To all whom it may concern:

Be it known that I, PETER AUGUST POPPE, a Norwegian subject, residing at Coventry, in the county of Warwick, England, have 5 invented certain new and useful Improvements in Valve Mechanism for Internal-Combustion Engines, of which the following is a specification.

This invention relates to valve mechanism for internal combustion engines in which the inlet and the exhaust valves are of the overhead kind. Usually, to obtain symmetrical arrangement of the valves by inclining them on each side of the longitudinal centre line of the engine, the camshaft is arranged centrally between them and operates the valves through rockers. With this arrangement, therefore, it is impossible to locate the sparking plugs between the 10 two valves in the centre of the combustion chamber, a position which is highly desirable for the purpose of avoiding detonation of the working charge under heavy loads. The object of the present invention, therefore, is to provide a simple method of actuating the valves, which will at the same time permit of placing the sparking plug in the centre of the head.

According to this invention, the camshaft 15 is situated at the side of the engine and is adapted to actuate the valve rockers upon both sides of the latter; those upon the side opposite to the camshaft by means of push rods extending between or at the sides of the cylinders, while those on the same side as the camshaft are actuated either directly from it, or indirectly through push rods, according as the camshaft is located adjacent the cylinder head or the crankcase.

40 In the accompanying drawings,

Figure 1 is a central vertical section through a cylinder showing one method of carrying out this invention.

Figure 2 is another section of the same 45 on a plane parallel to that of Figure 1.

In the construction shown in Figures 1 and 2, there is arranged at each side of the cylinder A a compartment B and C. In one of the compartments B is mounted the camshaft D, and preferably also the usual pivot E² upon which the rocker E is pivoted for direct engagement by the cam D². The compartment C upon the other side is provided with a similar pivot F² for the rocker F to actuate the valve G upon that side. The

rocker E actuates the valve H in the usual manner.

The preferred arrangement of the rockers is such that the arm E³ on which the cam bears is substantially parallel to the cylinder 60 axis, the other arms E⁴ and F³ bearing upon the valve stems in the usual manner.

A push rod J extends transversely to the cylinder axis through the head and is guided on the cylinder head. The push rod is put 65 in place previous to the mounting of the camshaft by providing an aperture B² in the wall of the compartment B of suitable size for its entry, the aperture subsequently being closed by means of a plug. The push 70 rod may be provided either with a pad or with a roller where it bears against its cam D³, and its opposite end acts upon the arm F⁴ of the rocker F. As the push rod is in a plane to one side of that containing the 75 valve stems, the rocker F would necessarily have its arms offset correspondingly, although in certain cases this might be reduced very considerably or wholly, by locating the two valves in a vertical plane which 80 was suitably inclined to the longitudinal axis of the engine to allow for the offset position of the push rods. It will be seen that the sparking plugs K can be located between the valves, as is desired.

With the foregoing construction it could be arranged that a single cam actuated the exhaust valve upon one side of the engine, and the inlet valve upon the other, the rocker for the one and the push rod for the other 90 bearing upon the one cam, but with this arrangement special modifications of the rockers would be necessary to ensure the correct timing of the valve in the known manner.

For lubrication purposes oil would be conveyed to either or both of the compartments B and C, but preferably to the one B, and thence, by a conduit, to that C, returning to the crankcase by way of the guide 100 tube Z for the inclined push rod.

It will be seen that in this construction the invention provides a very simple form of valve actuating mechanism, which ensures ready access to the working parts, while at 105 the same time providing a clear space between the two valves for the sparking plug. Ample provision is made for lubrication of the working parts, thus ensuring their quiet action.

What I claim as my invention and desire to secure by Letters Patent of the United States is:—

In an internal combustion engine, the combination of a cylinder head, a conical combustion chamber therein, an inlet valve seating upon one sloping side of said combustion chamber, an exhaust valve seating upon the other sloping side of said combustion chamber, an ignition device located in the apex of said combustion chamber between said valves, a cam shaft carried by said cylinder head within a compartment arranged on one side thereof and extending transversely of the cylinder axis, a rocker mounted in said compartment on one side of said cylinder head directly engaging one of said valves and said cam shaft, a second rocker mounted in another compartment on the opposite side of said cylinder head en-

gaging the other of said valves, a horizontal push rod within said cylinder head engaging said second rocker and said cam shaft, a bearing within said cylinder head for said push rod adapted to support it at both ends 25 and to form an oil duct connecting said compartments, and a cover for each of said compartments which encloses the rocker therein and also the end of said valves operated by it, the whole forming with the cylinder 30 head a unit construction of valves and valve operating mechanism, substantially as set forth.

In testimony whereof I have signed my name to this specification in the presence of 35 two subscribing witnesses.

PETER AUGUST POPPE.
